UNITED STATES PATENT OFFICE.

JAMES A. GRAY, OF SAN FRANCISCO, CALIFORNIA, ASSIGNOR TO AMERICAN CAN COMPANY, OF SAN FRANCISCO, CALIFORNIA, A CORPORATION OF NEW JERSEY.

APPARATUS FOR RE-FORMING CAN-BODIES.

1,306,810.

Specification of Letters Patent. Patented June 17, 1919.

Application filed September 30, 1915. Serial No. 53,370.

To all whom it may concern:

Be it known that I, JAMES A. GRAY, a citizen of the United States, residing at the city and county of San Francisco and State of California, have invented certain new and useful Improvements in Apparatus for Re-Forming Can-Bodies, of which the following is a specification.

The present invention relates to a machine for reforming can bodies, and more particularly for restoring such can bodies to their original cylindrical shape after they have been flattened, as for shipment and storage.

For reasons of economy, the bodies of cans designed to be used for the reception and preservation of food products or other material are first made in cylindrical form, and then flattened by compressing opposite sides, in order that such can bodies may occupy less space during shipment and storage. It is necessary, therefore, to restore these flattened can bodies to their original cylindrical shape before the first end or bottom can be applied thereto. The machine embodying the present invention accomplishes this reformation of flattened can bodies, and may be used, for example, by a packer who has received and stored his supply of cans, for the season's pack, in flattened form.

The object of this invention is to provide a machine for the above described purpose, which will reform flattened can bodies without in any way injuring the same, as by disrupting the metal or destroying the surface coating thereof.

In order to fully comprehend the invention, reference should be had to the accompanying sheets of drawings, in which—

Figure 1 is a perspective view of the can reforming machine, certain parts being broken away, and others being shown in phantom, to illustrate all the component parts of the machine and the relations therebetween.

Fig. 2 is a part-sectional elevation taken in the direction of the arrows in a plane represented by the line $x-x$ of Fig. 1.

Fig. 3 is a vertical section taken in the direction of the arrows along the line $y-y$ of Fig. 2, certain parts being broken away for the sake of clearness.

In the drawings, the numeral 1 represents any suitably constructed base or bed-plate, made of cast-iron or other suitable material,

and which is supported upon suitable legs 2,—Fig. 1 of the drawings. Mounted upon the bed 1 is a suitable super-structure 3, in which is journaled a horizontal drive-shaft 4. This shaft 4 constitutes the main driving means for the entire machine, and is shown in Fig. 1 of the drawings as carrying a belt-pulley 5 at one end, by means of which said shaft 4 may be driven.

A mutilated worm 6, meshing with a worm-wheel 7 mounted upon a shaft 8, imparts an intermittent rotary movement to said shaft 8. The shaft 8 is journaled in a super-structure 9, which is supported by the super-structure 3 and the bed-plate 1. A turret 10, in the present case mounted in a plane for vertical rotation, is secured to one end of the shaft 8, and at regular intervals about this turret 10, and near the periphery thereof, is a series of fixed outwardly projecting studs 11,—Fig. 2 of the drawings. Mounted for free rotation upon each stud 11 is a cylindrical mandrel 12, formed as shown in Fig. 2 with a tapering or conical end portion 12'. Suitable means are employed for retaining the mandrels 12 upon their respective studs 11, said means being shown in the drawings as comprising a screw 13 in the free end of each stud 11.

Another horizontal shaft 14,—Figs. 1 and 3 of the drawings, parallel to the shaft 8, is journaled in brackets 17 and 18 supported by the bed-plate 1, and is continuously driven by the drive-shaft 4 through suitable bevel gears 15 and 16. A yoke 19 is pivoted at one end concentric with the shaft 14, and in its other end carries a journal for a short shaft 21, said short shaft 21 being driven by the shaft 14 through suitable gear wheels 22 and 23, and carrying an ironing roller 20,—Figs. 2 and 3 of the drawings, positioned parallel to and for contact with the cylindrical portions of the mandrels 12, when said mandrels 12 are successively brought into position by the intermittent rotation of the turret 10. This contact between the roller 20 and one of the mandrels 12 is preferably secured by means of a plate 24,—Fig. 2 of the drawings, slidably mounted upon studs 25 fixed to the under side of the bed-plate 1, said plate 24 being pressed upward by springs 26, and supporting the free end of the yoke 19 by means of the pins 27.

Mounted upon the bed-plate 1 in front of the turret 10 are two spaced vertical brack-

ets 28,—Figs. 1 and 3 of the drawings, which support, by means of angle brackets 29, a magazine or holder 31^a for holding a supply of flattened can bodies 32 to be reformed 5 when required for use. Said magazine 31^a preferably comprises two opposite vertical side-plates 30 fastened to the brackets 29, and four vertical angle-plates 31 fastened one to each edge of each side-plate 30. The 10 lower part of the magazine 31^a is formed upon two sides by the oppositely disposed plates 33,—Fig. 3 of the drawings, which have inwardly projecting flanges 33^a upon which the lowermost flattened can body may 15 rest, and upon the other two sides by a stripper plate 30^a, formed as shown in Fig. 1 of the drawings, and an oppositely disposed plate 30^b,—Figs. 2 and 3 of the drawings, the function of said plates 30^a and 20 30^b being to guide the lowermost can bodies while the same are being spread just prior to removal from the magazine.

Immediately beneath the magazine thus formed is a horizontal guide plate 34, in 25 the guide-ways 36 of which is carried a sliding member 35,—Fig. 1 of the drawings. Horizontal reciprocating motion may be imparted to the slide 35 by any convenient means, shown in Fig. 1, as consisting of a 30 lug 37 on the under side of said slide 35, and a lever 38 connected to said lug 37 by a link 39, said lever being fulcrumed at 40^a to a bracket 40 attached to the frame of the machine, and connected by a rod 41 to an 35 eccentric strap 42 which embraces an eccentric 43 on the drive shaft 4.

Attached to the slide 35 are two spaced horizontal pointed rods 44, and between and parallel to said rods, and also attached 40 to the slide 35 is a cylindrical horn 45, formed preferably with a flattened, two-pronged end. The rods 44 and the horn 45 are adapted to be introduced through suitable openings in the stripper plate 30^a, by 45 the inward motion of the slide 35, between the sides of a flattened can body 32^a, in order to partly spread the same prior to the removal thereof from within the sphere of the magazine or holder, as illustrated in 50 Fig. 2 of the drawings. A pair of pusher-rods 46 are also attached to the slide 35 immediately below the level of the horn 45, said pusher-rods 46 being adapted to engage the lowermost partially spread and released can body 32^a and force the same over a positioned mandrel 12, as shown in Figs. 2 and 3 of the drawings.

On each side of the magazine 31^a is a pair of depending swinging fulcrumed arms 55 47 and 47',—Figs. 1 and 3 of the drawings, each of said arms being provided with an inwardly extended lower end having an inclined face 50 and a notch 52 in said face. These inwardly turned ends of the arms 47 and 47' are adapted to be inserted into the

sphere of the magazine 31^a through openings 51 in the walls thereof, to lift and support the entire stack of flattened can bodies 32 within said magazine, during a portion of the cycle of operation of the machine, and, 70 by means of the notches 52, to engage and slightly spread one of the lower can bodies, in order to permit of the entrance of the spreader rods 44 and the horn 45 as hereinbefore described. 75

The swinging arms 47 are fixed upon a short shaft 48, journaled in an extension of one of the brackets 28, and which carries an upwardly extending lever-arm 53. The opposite swinging arms 47' are fixed to 80 a shaft 49, journaled at one end in an extension of the opposite bracket 28 and at the other end in a bracket 56 suitably attached to the superstructure of the machine. This shaft 49 carries a depending lever-arm 54, 85 which is connected to the lever-arm 53 of the shaft 48 by the link 55, so that rotation of one shaft produces an opposite rotation of the other, and the arms 47 and 47' are thereby caused to swing in opposite directions. The shaft 49 is given a reciprocat- 90 ing rotating movement by any suitable means, as, for example, a lever 57 attached to said shaft 49, a rod 58 loosely attached to said lever 57, and a yoke 59 on the lower 95 end of the rod 58, said yoke straddling the drive-shaft 4 and having a cam-follower 60 adapted for engagement with a groove 61 of a cam 62 attached to said drive-shaft 4.

The shaft 8, carrying the turret 10, is hol- 100 low, and in the center thereof is carried a slid- 105 able, non-rotatable ejector rod 63, upon the forward or turret end 63^a of which is mounted a radially extended ejector arm 64, which is adapted to engage the inner edge of 110 a reformed can body for the ejecting of the same from its supporting mandrel. This rod is caused to slide longitudinally at cer- 115 tain periods in the cycle of operation of the machine, by a lever 67,—Fig. 1 of the draw- 120 ings, connected by a link 66 to a sleeve 65 mounted upon said rod 63. This lever 67, is fulcrumed at 68 to a suitable bracket 69 at- 125 tached to the frame of the machine, and its lower end is connected by a pin 70 to a con- 130 necting rod 71, the other end of which is pivotally attached to the reciprocating lever 38.

The operation of the machine may be de- 130 scribed as follows:—

Assuming that the magazine or holder 31^a contains a supply of flattened can bodies 32, and that the swinging arms 47 and 47' are so positioned that their ends intrude slightly into the lower part of the magazine 31^a, the 125 lowermost can body will then rest upon the inclined faces 50 of said arms 47 and 47', and the entire stack of can bodies will be sup- 130 ported thereby.

Now as the drive-shaft 4 is rotated, the 130

arms 47 and 47' are brought closer together, by means of the linkage described above, and the stack of can bodies is raised, by said inclined faces 50, within the magazine until 5 the side edges of the lowermost can body reach the notches 52 in the said faces 50, whereupon said lowermost can body is squeezed edgewise, due to the pressure exerted thereon by the continued inward movement 10 of the said fulcrumed arms 47 and 47', and its sides forced apart, as shown at 32^a in Fig. 3 of the drawings.

Further movement of the drive-shaft 4, through the medium of the eccentric 43, the 15 rod 41, and the lever 38, causes the slide 35, carrying the pointed rods 44 and the horn 45, to move inwardly, that is toward the magazine, while the swinging arms 47 and 47' remain in the position shown in Fig. 3 of the 20 drawings.

This inward movement of the slide 35 forces the pointed rods 44 and the horn 45 between the adjacent sides of the slightly spread can body 32^a, and by so doing further 25 spreads or opens the same, as shown in Fig. 2 of the drawings.

After passing sufficiently far into the can body 32^a to open the same evenly throughout its length, the rods 44 and the horn 45 are 30 withdrawn by the outward movement of the slide 35, the partially opened can body 32^a being retained within the magazine by the stripper-plate 30^a, and the arms 47 and 47', by the action of the cam 62, are swung outwardly, thus allowing the stack of can bodies 35 within the magazine 31^a to drop until the lowermost, partially opened can body assumes the position 32^b, Fig. 3 of the drawings, and rests upon the inwardly projecting 40 ledges 33^a. The arms 47 and 47' are then again swung inwardly, and the inclined faces 50, engaging the flattened can body immediately above the lowermost partially 45 opened can body, raise the entire stack within the magazine, with the exception of said lowermost partially opened can body, and, by reason of the pressure on the edges of the flattened body resting within the notches 52 of the said swinging arms, compress the can 50 body 32^a immediately above the released and partially reformed can body 32^b, as indicated in Fig. 3 of the drawings.

The next inward movement of the slide 35, which introduces the opening rods 44 and 55 horn 45 into the second can body 32^a, also brings the pusher-arms 46 into engagement with the partially opened and released lowermost can body 32^b, and thereby forces said can body 32^b from within the magazine 31^a 60 onto the mandrel 12, as shown in Fig. 2 of the drawings.

These operations are repeated at every inward stroke of the slide 35. That is, a can body 32^a, which has been slightly spread by 65 the arms 47 and 47', is further opened by the

rods 44 and the horn 45, and at the same time a can body 32^b, which has been partially opened by the previous stroke of the slide 35, is forced onto a mandrel 12 which has been brought into the position A, in axial alignment with the partially opened can body 32^b, Fig. 3 of the drawings, by partial rotation of the turret 10.

During the next complete reciprocating stroke of the slide 35, subsequent to forcing the can body 32^b onto the mandrel 12 at the position A,—Fig. 3 of the drawings, the turret 10 is step-rotated to bring said mandrel to the position B, during which time the can body on said mandrel is not acted on.

On the next stroke, however, the mandrel 12, with the can body thereon, assumes the position C, and said can body is brought into contact with the rotating ironing roller 20. The said can body and the mandrel 12 on 35 which it is supported, are revolved by the frictional contact of the can body with the said ironing roller 20, and said can body is thereby ironed out into a substantially true cylindrical body 32^c, and carried by the turret to position D, after which, by the step-rotations of the turret 10, the mandrel carrying the ironed can body 32^c is brought into position designated by the letter E, Fig. 3 of the drawings, where it is discharged from 95 the mandrel 12 by the ejector arm 64, which at this moment is thrown outwardly by the movement of the reciprocating ejector rod 63, actuated by the hereinbefore described means.

It will be readily understood from the foregoing that, when the machine is in operation, a number of can bodies are being acted on simultaneously, each in a different stage of reformation.

During every complete stroke of the slide 35, the turret 10 is advanced an amount equal to the angular distance between the mandrels thereon, so that at every such stroke, one flattened can body is brought into the sphere 110 of action of the machine from the magazine 31^a, and one reformed can body is discharged from the mandrel at the position E.

The particular form of machine herein described is that which is deemed to be most 115 practicable. It is understood, however, that variations may be made in the construction and arrangement of the working parts of the machine, without altering or in any way affecting the essential principles of the invention, and I therefore do not wish to be construed as limiting or restricting the invention in this regard.

Having thus described the invention what is claimed as new and desired to be protected 125 by Letters Patent is:—

1. In a machine for the described purpose, the combination of means for receiving and holding a deformed can body, feeding devices for successively applying deformed 130

can bodies in an axial direction to said receiving and holding means, and means associated therewith for engaging with the surface of a can body for ironing the same 5 into substantially cylindrical form, and means for spreading deformed can bodies prior to their reception on said holding means.

2. In a machine for the described purpose, 10 the combination of a smooth mandrel for receiving thereover cans in a deformed condition, automatic feeding mechanism for applying deformed can bodies in an axial direction on to said mandrel, a carrier for 15 holding said mandrel from endwise movement and transporting it to and away from said feeding mechanism, and rotatable means associated with said mandrel for engaging with the surface of a can body there- 20 on for reforming the same into substantially cylindrical condition.

3. In a machine for reforming flattened can bodies, the combination of a mandrel having a free end, automatic feeding means 25 for forcing can bodies successively endwise on to said mandrel, spreading means independent of the mandrel for enlarging the interior dimension of a can body relative to said mandrel, and ironing means co-operat- 30 ing with the mandrel.

4. In a machine for reforming flattened can bodies, the combination of a mandrel, automatic feeding means for forcing can bodies successively endwise on to said mandrel, spreading means for enlarging the rear ends of the can bodies before they are fed on to the mandrel, and ironing means co-operating with the mandrel.

5. In a machine for reforming flattened 40 can bodies, the combination of a mandrel having a free reduced end adapted to spread a can body, automatic feeding means for forcing can bodies successively endwise on to the mandrel, spreading means co-operat- 45 ing with said feeding means to spread the rear ends of the can bodies before they are advanced on to the mandrel, said feeding means causing the front ends of the cans to be spread by the mandrel, and ironing 50 means co-operating with the mandrel.

6. In a machine for reforming flattened can bodies, the combination of a mandrel having a free tapered spreading end, a carrier for the mandrel holding the same from 55 endwise movement, automatic feeding means for forcing can bodies successively on to the mandrel and thereby spreading said can body, and ironing means co-operating with the mandrel, said carrier operating to move 60 the mandrel to said ironing means and thence to said feeding means.

7. In a machine for the described purpose, the combination with a rotatable mandrel 65 for receiving deformed can bodies, of means for delivering the deformed can bodies in

an axial direction onto the said mandrel, an ironing roller associated with said mandrel for engaging the surface of a can body thereon for the ironing thereof to place the same into substantially cylindrical form, 70 and means for spreading deformed can bodies prior to their reception on said mandrel.

8. In a machine for the described purpose, the combination with a bodily movable mandrel for receiving deformed can bodies, of an 75 ironing roller for engaging the surface of a can body thereon for the ironing thereof to place the same in substantially cylindrical condition, mechanism for placing the mandrel within the sphere of the ironing roller, 80 and means for spreading deformed can bodies prior to their reception on said mandrel.

9. In a machine for the described purpose, the combination with a bodily movable and rotatable mandrel for receiving deformed can bodies, an ironing roller associated therewith for engaging with the surface of a can body thereon for the ironing thereof to place the same in substantially cylindrical condition, means for feeding a 90 deformed can body in an axial direction onto the rotatable mandrel, mechanism for placing the said mandrel within the sphere of the ironing roller, and means for spreading deformed can bodies prior to their recep- 95 tion on said mandrel.

10. In a machine for the described purpose, the combination of a bodily movable and rotatable mandrel held against longitudinal movement, means for feeding a deformed can body in an axial direction onto the said mandrel, an ironing roller associated with said mandrel for engaging with the surface of a can body thereon for the ironing thereof to place the same into sub- 100 stantially cylindrical form, means for moving the rotatable mandrel within the sphere of the ironing roller, and means for spreading deformed can bodies prior to their re- 105 ception on said mandrel.

11. In a machine for the described purpose, the combination with a mandrel for receiving deformed can bodies, of means for initially spreading the deformed can bodies and applying the same onto the said mandrel, and means associated with the said mandrel for engaging with the surface of a deformed can body thereon for the ironing thereof to restore the same to substantially 115 cylindrical form.

12. In a machine for the described purpose, the combination with a mandrel provided with a free tapering outer end portion for receiving axially and spreading cans in a deformed condition, of an ironing roller 125 associated with said mandrel for engaging with the surface of a deformed can body thereon for the ironing thereof to place the same in substantially cylindrical condition.

13. In a machine for the described pur- 130

- pose, the combination with a mandrel for receiving deformed can bodies, of means for feeding said can bodies axially onto the end of the said mandrel, means for spreading deformed can bodies, and means associated with the mandrel for engaging with the surface of a deformed can body thereon for the ironing thereof to restore the same to original form.
14. In a machine for the described purpose, the combination with a mandrel for receiving deformed can bodies, of means for automatically feeding said can bodies axially onto the end of the said mandrel, means for spreading deformed can bodies, and means associated with the mandrel for engaging with the surface of a deformed can body thereon for the ironing thereof to restore the same to original form.
15. In a machine for the described purpose, the combination with a mandrel for receiving deformed can bodies, and a holder for said can bodies, of devices for successively removing the bodies from said holder and applying the same onto the mandrel, means for spreading deformed can bodies, and means associated with said mandrel for engaging with the surface of the deformed can body thereon for the ironing thereof to restore the same to original form.
16. In a machine for the described purpose, the combination with a rotatable mandrel held against longitudinal movement, of a holder adapted to contain a stack of deformed can bodies, reciprocating means for successively removing said can bodies and applying the same onto the said mandrel, means for spreading deformed can bodies, and means associated with the mandrel for engaging with the surface of a deformed can body thereon for the ironing thereof to restore the same to original form.
17. In a machine for the described purpose, the combination with a rotatable mandrel, of a holder adapted to contain a stack of deformed can bodies, of reciprocating means for successively removing said can bodies and applying the same onto the said mandrel, means for spreading deformed can bodies, and means associated with the mandrel for engaging with the surface of a deformed can body thereon for the ironing thereof to restore the same to original form.
18. In a machine for the described purpose, the combination with a rotatable mandrel, of a holder adapted to contain a stack of deformed can bodies, of means for initially spreading the lowermost can body of the said stack, reciprocating means for removing such can body from within the holder and applying the same onto the mandrel, and means associated with said mandrel for engaging with the surface of a can body thereon for the ironing thereof to restore the same to original form.
19. In a machine for the described purpose, the combination with a rotatable mandrel, of a holder adapted to contain a stack of deformed can bodies, of means for initially spreading the lowermost can body of the said stack and means for applying the same onto the mandrel, and means associated with said mandrel for engaging with the surface of a can body thereon for the ironing thereof to restore the same to original form.
20. In a machine for the described purpose, the combination with a mandrel for receiving deformed can bodies, a holder adapted to contain a stack of deformed can bodies, means for initially spreading the lowermost body of the series of bodies contained within the holder, means associated with the holder for removing therefrom said initially opened can body and applying the same onto the mandrel, an ironing roller associated with said mandrel, and means for placing the mandrel within the sphere of the said roller so as to engage with the surface of the deformed can body on the mandrel for the ironing thereof to restore the same to original form.
21. In a machine for the described purpose, the combination with a series of mandrels, and an ironing roller associated with said mandrels, of devices for feeding deformed can bodies successively onto said mandrels, and means for successively placing the mandrels within the sphere of the ironing roller for engaging with the surface of a can body thereon for the ironing thereof to restore the same to original form.
22. In a machine for the described purpose, the combination with a series of rotatable mandrels, of means for placing deformed can bodies successively onto said mandrels, an ironing roller associated with the mandrels, and means for moving the mandrels successively within the sphere of the ironing roller to place the can body thereon into engagement therewith for the ironing thereof to restore the same to original form.
23. In a machine for the described purpose, the combination with a series of mandrels for receiving and holding a deformed can body, an ironing roller associated with said mandrels, means for forcing can bodies successively on to said mandrels, means cooperating with said forcing means for spreading flattened can bodies when so forced on to the mandrels, and means for imparting intermittent movement to said mandrels to place the same successively within the sphere of the ironing roller for engagement with the surface of a can body held thereon for the ironing thereof to restore the same to original form.
24. In a machine for the described purpose, the combination with a series of man-

- drels for receiving deformed can bodies, of means for automatically feeding deformed can bodies onto said mandrels successively, an ironing roller for engaging with the surface of a deformed can body on said mandrels for the ironing thereof to restore the same to normal condition, and means for moving the mandrels successively within the sphere of the ironing roller.
- 10 25. In a machine for the described purpose, the combination with a mandrel for receiving deformed can bodies, means for delivering deformed can bodies onto the said mandrel, an ironing roller associated with said mandrel for engaging with the surface of a deformed can body thereon for the ironing thereof to restore the same to normal condition, and means associated with the mandrel for ejecting a reformed can body therefrom, and means for spreading deformed can bodies prior to their reception on said mandrel.
- 15 26. In a machine for the described purpose, the combination with a series of mandrels for receiving thereon deformed can bodies, of mechanism for feeding deformed can bodies onto the mandrels successively, an ironing roller associated with said mandrels for engaging with the surface of a can body thereon for the ironing thereof to restore the same to original form, mechanism for successively placing the mandrels within the sphere of the ironing roller and removing the same therefrom on a can body being restored to original form, and means associated with each mandrel for automatically ejecting a reformed can body therefrom.
- 20 27. In a machine for the described purpose, the combination with a turret, of a series of mandrels carried thereby in spaced relation relative to one another, of means for feeding deformed can bodies onto said mandrels, an ironing roller for engaging with the surface of a can body held on the mandrels for the ironing thereof to restore the same to original form, mechanism for imparting rotary movement to the turret for moving the mandrels successively within the sphere of the ironing roller and removing the same therefrom on a can body thereon being restored to original form, and means associated with each mandrel for automatically ejecting the reformed can body therefrom.
- 25 28. In a machine for the described purpose, the combination with means for receiving axially and holding thereon deformed can bodies, feeding devices for automatically applying successively, deformed can bodies in an axial direction to said receiving and holding means, and rotary means associated therewith for engaging with the surface of a can body thereon for restoring the same to normal condition and means for spreading deformed can bodies prior to their reception on said mandrel.
- 30 29. In a machine for the described purpose, the combination with means for receiving and holding thereon deformed can bodies, and feeding devices for automatically and axially applying successive deformed can bodies to said receiving and holding means, of means associated therewith for engaging with the surface of a can body thereon for restoring the same to normal condition, and devices for automatically ejecting the reformed can body, and means for spreading deformed can bodies prior to their reception on said mandrel.
- 35 30. In a machine for the described purpose, the combination with a mandrel for receiving deformed can bodies, of a holder adapted to contain a stack of deformed can bodies, of a pair of swinging arms associated with the holder, means for swinging said arms inwardly for initially raising the stack within the holder and compressing the lowermost body of the stack therein and thence swinging the arms outwardly to lower the entire stack of bodies for placing the lowermost one thereof in axial alinement with the mentioned mandrel, reciprocating devices for engaging the lowermost can body on the inward throw of the swinging arms for partly reforming the same, reciprocating means for removing the lowered partly reformed can body and delivering the same onto the mandrel, and means co-acting with the mandrel for engaging with the surface of a deformed can body thereon and restoring the same to original form.
- 35 31. In a machine for the described purpose, the combination with a mandrel for receiving partly reformed can bodies, of a holder adapted to contain a stack of deformed can bodies, of means associated with the holder for partly reforming the lowermost body of the stack therein, means for removing the said partly reformed can body and placing the same onto the mandrel, and an ironing roller associated with the mandrel for engaging with the surface of a can body therein for restoring the same to original form.
- 40 32. In a machine for the described purpose, the combination with a series of rotatable mandrels mounted for free rotation, of a holder adapted to contain a stack of deformed can bodies, means associated with said holder for partly reforming the lowermost body of said stack of bodies and delivering said body onto a mandrel positioned to receive the same, an ironing roller for engaging with the surface of a can body on a mandrel for the ironing thereof to restore the same to normal condition, mechanism for moving the mandrels successively into and out of the sphere of the ironing roller, and

- means for automatically ejecting the reformed can bodies from the mandrels.
33. In a machine for the described purpose, the combination with a smooth mandrel individually rotatable and having a planetary revolution for receiving deformed can bodies, of means associated with the mandrel for engaging with the surface of a can body thereon for the ironing thereof to restore the same to original form, and means for ejecting the reformed can body from the mandrel, and means for spreading deformed can bodies prior to their reception on said mandrel.
- 15 34. In a machine for the described purpose, the combination with a mandrel mounted for free rotation and provided with a tapered receiving end, of means for delivering deformed can bodies onto said mandrel, an ironing roller co-acting with the mandrel for engaging with the surface of a deformed can body thereon and ironing the same to original form, and means for ejecting the reformed can body from off the mandrel.
- 20 35. In a machine for the described purpose, the combination with means for receiving deformed can bodies and partly reforming the same, of a mandrel for receiving said partly reformed can bodies, automatic feeding devices for delivering the partly reformed can body endwise onto the mandrel, ironing means co-acting with the mandrel for restoring the can body thereon to original form, and means for spreading deformed can bodies prior to their reception on said mandrel.
- 25 36. In a machine for the described purpose, the combination with means for receiving deformed can bodies and partly reforming the same, of a mandrel for receiving said partly reformed can bodies, devices for delivering the partly reformed can body onto the mandrel, means co-acting with the mandrel for restoring the can body thereon to original form, devices associated with the mandrel for automatically ejecting the reformed can body therefrom, and means for spreading deformed can bodies prior to their reception on said mandrel.
- 30 37. The combination with a holder adapted to contain a stack of deformed can bodies, of a series of mandrels for receiving thereon deformed can bodies, interconnected working instrumentalities associated with the holder for partly reforming the deformed can bodies and delivering the same successively onto the mandrels, means co-acting with the mandrels for restoring the partly reformed can body thereon to original form, mechanism for positioning the mandrels successively with respect to said means, and devices associated with the mandrels for ejecting therefrom reformed can bodies.
- 35 38. In a machine for the described purpose, a vertically disposed rotatable turret,

a series of spaced outwardly projecting spindles carried thereby, a mandrel mounted for free rotation on each of said spindles, said mandrels having tapered ends, means for feeding deformed can bodies onto said mandrels, an ironing roller for successively engaging with the surfaces of the can bodies held on the mandrels for the ironing thereof to restore the same to original form, and means for automatically ejecting the reformed can bodies from said mandrels.

39. In a machine for the described purpose, a vertically disposed rotatable turret, a series of spaced outwardly projecting spindles carried thereby, a mandrel mounted for free rotation on each of said spindles, said mandrels having tapered ends, means for feeding deformed can bodies into said mandrels, an ironing roller for successively engaging with the surfaces of the can bodies held on the mandrels for the ironing thereof to restore the same to original form, means for intermittently rotating said turret to bring said mandrels successively into and out of engagement with said ironing roller, means for rotating said ironing rollers, and means for automatically ejecting the reformed can bodies from said mandrels.

40. In a machine for the described purpose, a series of freely rotatable mandrels for receiving deformed can bodies mounted in spaced relation upon a vertically disposed turret, a holder adapted to contain a stack of deformed can bodies, a pair of oppositely operating swinging arms associated with the holder for raising the stack of can bodies within the holder and compressing the lowermost body of said stack, a reciprocating sliding member for partly reforming said compressed can body and for subsequently feeding the same onto a positioned mandrel, means co-acting with said mandrel for engaging with the surface of the deformed can body thereon to restore the same to original form, means for intermittently rotating said turret to bring said mandrels successively into position for receiving deformed can bodies, and means for operating said swinging arms and said reciprocating slide.

41. In a machine for the described purpose, a mandrel for receiving a deformed can body, a holder adapted to contain a stack of deformed can bodies, a plurality of pairs of oppositely operating swinging arms, having inwardly extending portions adapted to move within the lower portion of said holder for initially raising the stack of can bodies therewithin and compressing the lowermost body of said stack, and to be withdrawn to lower said stack for placing the lowermost body thereof in axial alignment with said mandrel, a reciprocating slide for feeding said lowermost can body onto said mandrel, an opening horn carried by said slide and adapted to be inserted into

the can body compressed by said swinging arms to partially reform the same, an ironing roller for engaging with the surface of the can body carried by said mandrel to re-
5 store the same to original form, means for moving said mandrel from the sphere of action of said feed slide to the sphere of action of said ironing roller, means for rotat-
ing said roller, and means for operating
10 said swinging arms and said slide, and means for automatically ejecting the reformed can body from said mandrel.

42. In a machine for the described purpose, the combination with a holder adapted
15 to contain a stack of deformed can bodies, primary means for removing the lowermost body from within said holder, secondary means for receiving and holding the said removed can body, a member associated with
20 therewith for engaging with the surface of a held can body for the ironing thereof to restore the same to original form, and means for spreading deformed can bodies prior to their reception on said holding means.

25 43. The combination of can body spreading means, a series of mandrels movable successively to a receiving station and a reforming station; means for moving said mandrels intermittently to stop at said stations; can body feeding means at said receiving station; and can body reforming means at said reforming station.

44. The combination of a series of rotatable mandrels movable successively to a receiving station and to a reforming station; means for moving said mandrels intermittently to stop at said stations; can body feeding means at said receiving station; and can body ironing and reforming means
40 at said reforming station.

45. The combination of a series of mandrels movable successively to a receiving station, and to a reforming station; means for moving said mandrels intermittently to stop at said stations; can body feeding means at said receiving station; and a can body reforming roller at said reforming station.

46. The combination of a series of mandrels movable successively to a receiving station, a reforming station and an ejecting station; means for moving said mandrels intermittently to stop at said stations; can body feeding means at said receiving station; can body reforming means at said reforming station; and can body ejecting means at said ejecting station.

47. In a can body reforming machine, in combination: means for reforming can bodies arranged to apply internal and external pressure on the same; and means for applying external pressure on the deformed can bodies in the direction of their greater diameters, and acting in advance of said reforming means.

48. In a can body reforming machine, in combination: means for partly opening the deformed can, comprising oppositely movable pressure elements, and devices for moving them against the deformed can in the direction of its greater diameter; and a tapered mandrel and ironing means for reforming such partly opened can.

In testimony whereof I have signed my name to this specification in the presence of two subscribing witnesses.

JAMES A. GRAY.
